(57) **CLAIM**

The ornamental design for a laboratory mill as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front left perspective view of a laboratory mill according to the design;

FIG. 2 is a front top perspective view thereof; and,
FIG. 3 is a front top perspective view thereof, showing a portion of the laboratory mill in an alternate position.

The bottom side and the rear side of the laboratory mill are not part of the claimed design.
